UNITED STATES PATENT OFFICE.

GUSTAV SCHÖNGUT, OF BUDAPEST, HUNGARY.

MANUFACTURE OF WINDINGS FOR ELECTRICAL MACHINES.

1,282,956.

Specification of Letters Patent. Patented Oct. 29, 1918.

Application filed March 11, 1915. Serial No. 13,608.

To all whom it may concern:

Be it known that I, GUSTAV SCHÖNGUT, civil engineer, a subject of the King of Hungary, and resident of Budapest, in the 5 Kingdom of Hungary, Austro-Hungarian Empire, have invented an Improvement in the Manufacture of Windings for Electrical Machines, of which the following description, in connection with the accompanying 10 drawings, is a specification, like characters on the drawings representing like parts.

This invention relates to the manufacture of windings for electrical machines and will be best understood by reference to the following description, taken in connection with the accompanying drawings, of one specific apparatus for carrying the same into effect embodying the invention, it being understood that the invention in its true scope 20 will be more particularly pointed out in the appended claims.

In the drawings,

Figure 1 is a diagrammatic side view of one form of apparatus, selected for illustrative purposes, to which the present invention 25 relates;

Fig. 2 is a plan view of the apparatus shown in Fig. 1 in one operative position;

Fig. 3 is a plan view of the form of apparatus shown in Fig. 1, in another operative position from that shown in Fig. 2;

Fig. 4 shows, at the right a closed slot and at the left a partly closed slot, for the reception of the windings.

As is well known, the windings in electrical machines are disposed in slots. These slots are either wholly closed, Fig. 4, or the slit 8 of the slot 3 for the reception of the wire 1 is so narrow that the wires cannot be 35 introduced into the slot through said slit but must be drawn in through the slot itself, the slot in such case being the so-called partly closed slot. The laying or drawing of the wires into the slot or slots has heretofore, so far as applicant is aware, been effected wholly by hand, and consequently is 40 at best a slow and tiresome operation presenting many disadvantages, the wires, for example, lying upon the ground where they 45 take up considerable space and being bent back and forth during the drawing-in or laying-in operation, whereby the insulation 50 is very liable to injury.

The present invention aims, among other 55 things, to overcome the disadvantages or objections above set forth, the drawing

through of the wire, when once its free end has been introduced into or passed through the slot by hand, being effected in accordance with the present invention by suitable 60 apparatus.

In the illustrative form of apparatus shown for carrying the invention into effect, take-up means for the wire is provided, said take-up means herein including two drums 65 each of which is mounted for swinging movement about an axis perpendicular to its axis of rotation and upon which two drums the wire is alternately wound and unwound. The provision for swinging each drum about 70 an axis perpendicular to its axis of rotation is to facilitate the unwinding of the wire from the drum, as will be hereinafter more fully described.

The electrical machine to receive the 75 windings will preferably be placed upon a table or other suitable support, said table or support being preferably adjustable vertically and horizontally in guides or ways 80 c, d, respectively. The free end of the wire 85 is passed through the slot 3 by hand and is then connected or secured to the free edge of one of the drums, to the drum f' situated at the right in Figs. 1, 2 and 3 for example. The winding surface of the drum will preferably be of sufficient extent to receive all 90 the wire in a single layer. It is understood, of course, that the other end of the wire has previously been secured to a suitable part of the electrical machine. By rotation of the 95 drum f' all the wire with the exception of that portion thereof contained in the slot 3 will be wound up on the said drum from its outer edge to its inner edge. During this winding operation the drum f' will be in the position at right angles to the position shown in Fig. 2, that is to say in the position in which said drum f' is represented as being in Fig. 3. The drum f' is now swung about the axis h, into the position shown in 100 Fig. 2, the end of the wire previously secured to the outer edge of the drum f' is detached therefrom and passed by hand through another slot of the machine e, from the right side of said machine Fig. 2 to the 105 left side thereof, and the end of the wire is secured to the outer edge of the drum f. If the latter drum be now rotated the wire will be drawn through the slot and off of the drum f' until all of the wire has been 110 wound up on the drum f with the exception of that portion of the wire contained in the

two slots and extending from the first slot to the second, this latter portion being drawn closely against the end face of the machine and wiped into correct position thereagainst 5 by the operator in the usual way by means of a pattern or other suitable tool.

The end of the wire secured to the outer edge of the drum f is now detached therefrom, passed through another slot in the 10 machine e and secured to the outer edge of the drum f' . The drum f is now swung from the position shown in Fig. 2 about its axis h into the position shown in Fig. 3, or it may be swung into this position before 15 passing the wire through the slot in the machine e . By rotating the drum f' the wire will be drawn through this latter slot and placed in proper position therein. Before rotating the drum f' to wind the wire 20 thereon, said drum will have been swung about its axis h from the position shown in Fig. 2 into that shown in Fig. 3.

It will thus be seen that by the rotation of first one and then the other drum f , f' , 25 the wire will be drawn first in one direction and then in the opposite direction through the slots of the electrical machine, and will be wound alternately first upon one and then upon the other of said two drums, 30 until the winding operation has been completed.

The drum from which the wire is being unwound does not rotate during the unwinding of the wire therefrom but remains 35 stationary, said drum being in the position occupied by the drum f for example in Fig. 3, and it will be noted that the wire is drawn off from the drum in successive coils, axially of the drum, which greatly 40 facilitates the operation.

In accordance with the present invention, controlling means is provided to insure that only one coil of wire shall be drawn off of a drum at a time, said means in the illustrative embodiment of the invention including suitable members, such as levers i mounted for swinging movement on pivots k provided at the rear edge of drums f , f' . When the wire is being wound upon a drum 50 f or f' these arms or levers i are swung into the position shown in the case of drum f in Figs. 1 and 2 and of drum f' in Fig. 3, said arms or levers then extending radially outward from the edge of the drum, but 55 when the wire is being unwound from the drum said arms or levers i are swung into a position in which they extend transversely of the winding surface of the drum as shown in the case of drum f' at the right in Figs. 1 and 2 and in the case of drum f , at the left in Fig. 3. In this position the arms i are preferably held against the winding surface of the drum by yielding means 60 such as a spring (not shown). Said levers or arms i may be moved from one position 65

to the other by any suitable operating means such as a lever (not shown).

The drums will preferably be rotated by independent means, such for example as an electric motor connected thereto by a clutch 70 provided with suitable operating mechanism (not shown).

The electrical machine to receive the windings will preferably be so adjusted vertically and horizontally that the slot intended to receive the winding shall be positioned so as to register longitudinally with the path of movement of the wire as the latter is unwound from one drum on to the other one. Any suitable means (not shown) 80 may be provided for securing or locking the drums in their winding or unwinding position.

It is to be understood that while the invention is herein shown as embodied in a 85 specific apparatus, the invention is not to be considered as circumscribed or limited to the details illustrated of said apparatus, or any of them, but that the said details may be variously modified without departing 90 from the spirit of the invention, the true scope of which is more particularly set forth in the appended claims.

Claims:

1. Apparatus for effecting the winding 95 in electrical machines including, in combination, take-up apparatus located at opposite sides of the electrical machine to be wound and adapted to take up the wire after the free end thereof is passed through 100 the slots in the machine alternately in opposite directions and to deliver the wire; and means upon which said apparatus are swingingly mounted, whereby said apparatus can be turned from wire receiving into wire delivering position, and vice versa.

2. Apparatus for effecting the winding in 110 electrical machines including, in combination, a support for the electrical machine to be wound; means vertically to adjust said support; and take-up apparatus located at opposite sides of said support and adapted to take up the wire after the free end thereof is passed through the slots in the machine 115 alternately in opposite directions and to deliver the wire; and means swingingly to support said take-up apparatus, whereby said apparatus can be moved from wire receiving into wire delivering position, and vice versa.

3. Apparatus for effecting the winding in 125 electrical machines including, in combination, a support for the electrical machine; means horizontally to adjust said support; and take-up apparatus located at opposite sides of said support and adapted to take up the wire after the free end thereof is passed through the slots in the machine alternately in opposite directions and to deliver the wire; and means swingingly to support said 130

take-up apparatus, whereby said take-up apparatus can be moved from wire receiving into wire delivering position, and vice versa.

4. Apparatus for effecting the winding
5 in electrical machines including, in combination, a support for the electrical machine to be wound; rotatable take-up drums for the wire, located at opposite sides of said support; and means upon said drums, movable
10 able into and out of operative position, for controlling the unwinding of the wire from said drums.

5. Apparatus for effecting the winding in electrical machines including, in combination, a support for the electrical machine to be wound; means vertically to adjust said support; rotatable take-up drums for the wire, located at opposite sides of said support; and means upon said drums, movable
20 into and out of operative position, for controlling the unwinding of the wire from said drums.

6. Apparatus for effecting the winding in electrical machines including, in combination, a support for the electrical machine to be wound; means horizontally to adjust said support; rotatable take-up drums for the wire, located at opposite sides of said support; and means upon said drums, movable
30 into and out of operative position, for controlling the unwinding of the wire from said drums.

7. Apparatus for effecting the winding in electrical machines including, in combination, a support for the electrical machine to be wound; rotatable take-up drums for the

wire, located at opposite sides of said support; means to support each of said drums for swinging movement about an axis perpendicular to its axis of rotation; and means 40 upon said drums, movable into and out of operative position, for controlling the unwinding of the wire from said drum.

8. Apparatus for effecting the winding in electrical machines including, in combination, a support for the electrical machine to be wound; rotatable wire take-up and delivery drums, located at opposite sides of said support; and means to support each of said drums for swinging movement about an axis 45 perpendicular to its axis of rotation, whereby each of said drums may be brought alternately into wire-receiving and wire-delivering position.

9. Apparatus for effecting the winding in electrical machines including, in combination, rotatable take-up and delivery drums located at opposite sides of the electrical machine to be wound, each of said drums being provided with a flange around one edge, 60 the other edge being flangeless; and means to support said drums for swinging movement each about an axis perpendicular to its axis of rotation.

In testimony whereof I have signed my 65 name to this specification, in the presence of two subscribing witnesses.

GUSTAV SCHÖNGUT.
